UNITED STATES PATENT OFFICE.

JOHN H. ZORN, OF CHICAGO, ILLINOIS.

ADJUSTABLE CORSET APPLIANCE FOR RUPTURES.

1,413,649.

Specification of Letters Patent. Patented Apr. 25, 1922.

Application filed March 18, 1921. Serial No. 453,418.

To all whom it may concern:

Be it known that I, JOHN H. ZORN, a citizen of the United States, and a resident of the city of Chicago, in the county of Cook and State of Illinois, have invented certain new and useful Improvements in an Adjustable Corset Appliance for Ruptures; and I do hereby declare that the following is a full, clear, and exact description of the same, reference being had to the accompanying drawings, and to the numerals of reference marked thereon, which form a part of this specification.

10 My invention is related to a corset of the sort in which a canvas or other fabric belt is worn supplied with pads which must be correctly located to perform the desired function.

15 It is an object of this invention to so secure the pads to the fabric that their position may be readily adjusted and that they may then be securely fastened in the correct position.

20 It is a further object of this invention to provide slots through the securing plate and the fabric and to prevent the edges of the fabric where the slots are made from raveling.

25 It is a further object of this invention to so locate the slots in pads and to make said slots of such a form that the pads may be readily moved in all directions parallel to the fabric.

30 Other and further important objects of this invention will be apparent from the disclosures in the specification and drawings.

The invention (in a preferred form) is illustrated in the drawings and hereinafter more fully described.

35 On the drawings:

Figure 1 is a front view of the corset with the pads secured thereto.

Figure 2 is a view on an enlarged scale of one of the pads.

40 Figure 3 is a side view of the same pad, the view being partly in section on the line 3—3 of Figure 2.

45 Figure 4 is a section similar to one taken on line 4—4 of Figure 1, but showing a modified construction.

As shown on the drawings:

The corset 1 of canvas, heavy ducking or other fabric has the usual fastening means 2 for uniting its ends. Elastic straps 3 and 4 are provided on the belt for holding the pads in place. The pads are provided with

5 studs 5 and 6 over which key hole fixtures on the ends of the straps 3 and 4 engage. One end of each of the straps 3 is secured to the front of the corset. The rear ends of 60 the straps 4 are attached to the back of the corset and are provided with buckles to permit the length of the straps 4 to be varied. The pad proper comprises a stuffed member 65 21 having a plain face 18 to which is secured a leather or wooden base 17. Two pieces of leather 7 and 8 of the shape and size of this base are cemented to the two faces of the corset in approximately the position that the pad should occupy. By means of a die 70 slots are cut in the two pieces of leather and in the fabric at one operation.

There is a slot 10 going longitudinally of the pad and slots 12 and 13 parallel thereto and near one end of the pad. The 75 inner ends of these slots are located at approximately the greatest width of the pad. A slot 11 crossing the slot 10 near one end unites the slots 12 and 13 near their middle. Another cross-slot 14 is provided near the 80 other end of the slot 10. These cross-slots are curved, the curvature being very slight, that is the radius of the curve is very long, so that the center of the curve would be off the pad. This enables the pad to be 85 moved sideways more easily than it could through perfectly straight slots, because the direction of the length of the pad will need to be altered slightly when the pad is lifted or lowered relative to the corset, to fit different cases.

A plate of metal 9 is provided of the same shape and size as the leather plates 7 and 8 and the wooden base member 17. Slots similar to those described are also provided 95 in this plate. Screws 15 are introduced through the slots, each screw carrying a washer 16 beneath its head. The screws enter the wooden base 17 and are held in place thereby. Their distance apart is equal 100 to the distance between the cross-slots 11 and 14 measured along the straight slot 10. By tightening the screws, the plate 9 will clamp the fabric 1 between said plate 9 and the base member 17, thus frictionally holding the pad in place. When the screws are loosened the pad and the plate 9 may be moved relative to the corset 1 because of the slots.

110 In the manufacture of this device the leather pieces 7 and 8 are cemented to the corset fabric 1 at the place nearest to the

average need for a pad. The leather pieces and the canvas are then cut simultaneously to provide the slots. The pads and plates 9 are provided separately.

5 When the corset is to be fitted to an individual the pad (if one is sufficient) or the pads 21 (if two are needed) are separated from the plates 9 by having the screws 15 completely removed. Each pad 21 is then 10 placed on the inside of the corset and the plate 9 on the outside of the corset with the slots in the plate registering with the slots in the corset. The screws are then replaced in the pad through the slots with the 15 washers 16 in place. If the pad 21 needs to be moved sideways to fit the needs of the individual it will ordinarily need also to be turned through a small angle. This motion can be accomplished by sliding the pad so 20 that the screws enter the cross slots 11 and 14. The curved character of these slots enables both of these motions to be accomplished without binding. If the pad needs to be adjusted lengthwise only, this can be 25 done from the original position, by letting the screws travel along the one slot 10. The dotted lines in Figure 2 represent an unusual case in which the pad has first been rotated with the screw at the cross-slot 14 30 remaining in the slot 10 until the other screw has entered the slot 13. The pad has then been moved approximately lengthwise until the last named screw arrives at the end of the slot 13. The first screw travels 35 in the slot 10 during this motion. If a still greater rotation of the pad is needed the lower screw may be made to enter the lower half of the slot 14 instead of traveling along the slot 10. The correct position 40 for the pad 21 having been found, the plate 9 is moved into a position in register with the base 17 and the screws 15 tightened. The fastenings or key hole fixtures on the ends of the straps 3 and 4 are then engaged 45 over the studs 5 and 6 and the corset is ready for use.

Figure 4 illustrates a modified form of a key hole fixture 22 having integrally formed thereon a flexible metal clip or tongue 20 50 which is adapted to contact the head of a stud 5 or 6 to hold said key hole fixture in place against accidental release from a stud on which it is engaged.

I am aware that numerous details of con-

struction may be varied through a wide 55 range without departing from the principles of this invention, and I therefore do not purpose limiting the patent granted otherwise than necessitated by the prior art.

I claim as my invention:

1. A corset of fabric, having intersecting slots therein, and leather reinforcing means cemented to each face of said fabric, and having slots registering with said first named slots.

2. A plate having slots therein, clamping screws through said slots, certain of said slots being parallel and being connected by cross slots, the cross slots being curved to a radius extending beyond the plate.

3. A plate having three parallel slots therein, and having other slots crossing the central one of said parallel slots, one of said cross slots connecting the outer parallel slots, clamping screws traversing said slots, and a body into which said screws enter and by which they are held at a fixed distance from each other, said distance equaling the distance between the cross slots along the central one of the parallel slots.

4. In a surgical appliance, a corset, a pad, elastic straps connected to said corset, and a detachable connection between each of said straps and said pad including a member secured to the strap and having a key hole shaped opening therein and a stud on said pad, said member having an upstanding tongue overlapping the head of said stud.

5. In a pad support, a plate having two curved parallel slots, screws, one through each of said slots, and a base into which said screws enter and to which the pad is secured.

6. A corset of textile fabric, a pad having a stiff base, a metal plate adapted to register with said base, and fastening means whereby said pad can be secured to one face of said corset and said plate to the opposite face thereof in position to register with said base.

In testimony whereof I have hereunto subscribed my name in the presence of two subscribing witnesses.

JOHN H. ZORN.
